FREDERICK C. WESTPHAL, OF NEW BRUNSWICK, NEW JERSEY.

GAME DEVICE.

1,401,844.

Specification of Letters Patent. Patented Dec. 27, 1921.

Application filed September 25, 1920. Serial No. 412,824.

To all whom it may concern:

Be it known that I, FREDERICK C. WESTPHAL, a citizen of the United States, residing at New Brunswick, in the county of Middlesex and State of New Jersey, have invented new and useful Improvements in Game Devices, of which the following is a specification.

This invention relates to game apparatus. 10 More particularly the invention relates to devices or apparatuses with which the well known game of baseball is played.

Some of the objects of the present invention are: to produce a game device of the 15 character mentioned in the simplest possible form; to produce a simple game device with which, and an understanding between opponents, as regards rules, the divers offensive and defensive acts and plays, on the 20 one hand, may be indicated by the turning of a card, and the placing on, and the removal from the bases forming a part of the device, of elements representative of "base-runners," in accordance with the 25 indicia on the turned card, on the other hand; to produce a game device in which there is utilized what will hereinafter be referred to as an "extra set of cards" having indicia thereon, the "extra set of cards" being 30 brought into play when a particular card having particular indicia thereon of another set of cards is turned up to minimize the 35 number of cards and at the same time having the advantage of making substantially all possible plays. With these and other 40 objects in view the invention resides in the particular provision of parts and the rules which govern in the playing of the game hereinafter more fully described and illustrated in the accompanying drawing, in which:

The figure is a plan view of the device 45 of the present invention showing the playing field and the cards used in playing the game, which playing field and cards are shown as forming parts of a single blank; the cards to be cut from the blank. The game device may be marketed in a single blank or the same may be marketed in parts 50 as will be understood.

Referring more particularly to the drawing, it will be seen that, the device of the present invention consists preferably of piece of any suitable material 10, such as paper-board 55 or the like, which is marked off in sections 11 and 12. The section 11 has defined

thereon a playing field 13 in simulation of a baseball playing field of the regulation type. The said field 13 consists of an infield 14, and an outfield 15, and the usual bases 16. 60 The playing field is done in colors and it includes representations of players and player's benches. The section 12 is marked off in smaller sections 17, and sections 18. The sections 17 bear indicia 19; Foul, Strike, 65 Out, Hit, Ball For One Base, Two Base Hit, Three Base Hit, Home Run, Fly Out, Hit Out, Foul Out, Out at First, Out at Second, Out at Third, Long Fly Hit. The sections 18 bear indicia 20, viz; Foul, Out, Three 70 Base Hit, and Home Run. The sections 17 and their indicia constitute one set of cards, and the sections 18 and their indicia constitute an "extra set of cards." Elements 21 which may be of any preferred shape are 75 representative of and are used as "base runners."

The indicia that appears upon the cards is self explanatory of what will occur, or what must occur in the playing of the game in 80 accordance with promulgated and recognized rules and regulations. It therefore goes without saying that the individuals participating in the game must have knowledge of such rules and regulations, but not necessarily each and every rule and regulation 85 of the game.

To play the game of baseball with the device of the present invention, the following directions are adhered to:

The individual or individuals on the inside, or the offense has the opportunity to turn over any one of the cards of the set constituted by the sections 17. The indicia on the particular card turned over indicates 95 what the "batter" has done and the game progresses in accordance therewith. In the event that a card bearing the indicia "Two Base Hit" is turned over, one of the elements 21 is placed on second base. If that 100 is followed by the turning over of the card bearing the indicia "Home Run," then of course, there shall be two scores, etc. When one side is retired the other side is on the offensive with the opportunity to score. 105 The cards that are turned over are not put back into the pile until "three out" has been registered. When a card bearing the indicia "Long Fly Hit" has been turned over, the participant is entitled to pick from the extra set of cards hereinbefore referred to, and after reading and playing as that card indi- 110

cates, the participant replaces it with the remaining four cards of the extra set face down. If "Out at First Card" is turned over and a base runner is on first base, that 5 means that there is one out, whereas if first base is unoccupied, then it is assumed that the batter hit but was put out. Baserunners on second and third bases would be affected only by the turning over of the cards "Out 10 at Second" and "Out at Third," as will be understood.

What is claimed is:

1. In a game device as characterized, a plurality of elements representative of baserunners, a playing field including bases, a set of 15 50 cards each bearing indicia in accordance with which one of said elements is placed on or removed from one of said bases, and an extra set of 5 cards each bearing indicia

which construed with certain indicia of 20 cards of said first set indicate that one of said elements should be placed on or should be removed from one of said bases.

2. In a game device as characterized, a plurality of elements representative of baserunners, a playing field including bases, a plurality of sets of 50 cards one of said sets being an extra set, each card of each set bearing indicia, certain 5 cards of one set bearing indicia requiring the exposition of 25 the indicia of a certain card of the other extra set to be construed therewith to indicate the placing of one of said elements on one of said bases or the removal of one of said elements from one of said bases. 30

In testimony whereof I hereby affix my signature.

FREDERICK C. WESTPHAL.
